UNITED STATES PATENT OFFICE.

CHARLES HYLAND, OF PITTSBURGH, PENNSYLVANIA, ASSIGNOR TO FLANNERY BOLT COMPANY, OF PITTSBURGH, PENNSYLVANIA.

STAY-BOLT STRUCTURE FOR BOILERS.

Specification of Letters Patent. Patented Apr. 10, 1917.

1,222,292.

Application filed February 26, 1916. Serial No. 30,682.

To all whom it may concern:

Be it known that I, CHARLES HYLAND, a citizen of the United States, and a resident of Pittsburgh, in the county of Allegheny and State of Pennsylvania, have invented 5 certain new and useful Improvements in Stay-Bolt Structures for Boilers; and I do hereby declare the following to be a full, clear, and exact description of the invention, 10 such as will enable others skilled in the art to which it appertains to make and use the same.

This invention relates to improvements in stay bolt structures for boilers,—one object 15 of the invention being to provide a simple device for connecting the head of a stay bolt with the outer boiler sheet in such manner as normally to retain the head of the bolt on its seat with yielding pressure and to permit slight longitudinal and lateral movement 20 of the bolt and prevent undue strain upon either of the boiler sheets through which the stay bolt passes.

A further object is to provide, in a boiler 25 stay bolt structure, a yielding device connecting one end of the bolt with the outer boiler sheet, and to so construct said device that it will expose the tell-tale hole of the bolt and also provide a steam and water 30 tight connection between the head of the stay bolt and the outer face of the outer boiler sheet.

With these and other objects in view, the invention consists in certain novel features 35 of construction and combinations of parts as hereinafter set forth and pointed out in the claims.

In the accompanying drawings; Figure 1 is a sectional view illustrating an applica- 40 tion of my improvements, and Fig. 2 is a sectional view showing a modification.

1 represents a stay bolt having one of its ends adapted for attachment to the inner sheet 2 of a fire box or boiler and the outer sheet 45 of this bolt is provided with a head 3 which, as shown in Fig. 1, may be partly spherical and may also be provided with a tell-tale 4. The head 3 passes through a hole in the outer boiler plate 5 and a portion of 50 the wall of this hole affords a bearing 6 for the partly spherical head of the bolt.

The head of the bolt is made with an enlargement forming a shoulder 7 and having less diameter than that of the adjacent 55 partly spherical portion of the head, where-

by an annular face or shoulder 8 is formed on the end of the latter at right angles to the axis of the bolt, and upon said beveled enlargement, an angular extension 9 is formed.

An annular cap 10 of spring-metal, bent partially upon itself so that it shall comprise two oppositely disposed members and possess adequate resiliency or flexibility, encircles the head of the bolt so that its inner edge 11 will rest against the flat annular shoulder 8 of said bolt head,—the edge 12 of the outer fold or member of said cap being disposed in a groove 13 in the outer face of the boiler sheet 5. The groove 13 70 serves as convenient centering means for the cap relatively to the bolt, and it also serves to receive material whereby the flexible cap is welded to the boiler sheet 5 as indicated at 14. The inner edge portion of the inner fold of the annular flexible cap is welded, as at 16 to the beveled shoulder 7 on the bolt head.

In the form of the invention shown in Fig. 2, the head 3 of the bolt is shown as being 80 spherical and provided with an annular shoulder 17 upon which one edge of the annular flexible cap 10 rests,—the other edge of said cap resting against the outer boiler sheet 5. In this construction, one edge of the 85 cap is welded to the spherical head of the bolt, as indicated at 18, while the other edge of said cap is welded to the face of the outer boiler sheet 5, as shown at 19.

In both forms of the invention, the flexible 90 or resilient cap 10 will permit sufficient play of the bolt head in the outer boiler sheet to compensate for relative movements of the boiler sheets due to expansion and contraction, and at the same time effect a water and 95 steam tight connection between the bolt head and the outer boiler sheet. While performing these functions, the resilient cap also exposes the tell-tale hole of the bolt.

If desired, the resilient cap may contain 100 lubricant which will find its way between the bolt head and its bearing in the boiler sheet 5 and serve to protect the bearing surfaces and insure the flexibility of the connection of the bolt with the boiler sheet.

I do not claim in this case, broadly, a yielding cap to encircle the head of a stay bolt and comprising a part secured to the boiler sheet and a part pressing against the stay bolt in an inward direction,—such con- 110

struction being claimed in copending application filed by D. E. B. Stafford and Ethan I. Dodds, February 29, 1916, Serial No. 81,260.

- 5 Various slight changes might be made in details of construction of my invention without departing from the spirit thereof or limiting its scope and hence I do not wish to restrict myself to the precise details here-
10 in set forth except as defined by the scope of the appended claims.

Having fully described my invention what I claim as new and desire to secure by Letters-Patent, is:-

- 15 1. In a stay bolt structure, the combination with a boiler sheet and a stay bolt having a head mounted therein, of a flexible metal cap secured at one edge to the boiler sheet and secured at its other edge to the head of the bolt and normally pressing against the same in a direction parallel to the axis of the bolt.
20 2. In a stay bolt structure, the combination with a boiler sheet and a stay bolt having a head mounted therein, of an annular flexible cap encircling the bolt head and welded at its respective edges to the boiler sheet and to said bolt head.
25 3. In a stay bolt structure, the combination with a boiler sheet and a stay bolt having a head mounted therein, said head having an annular shoulder, of an annular flexible cap having one edge bearing against the shoulder on the bolt head, and means se-
30 curing the other edge of said annular flexi-
35 ble cap to the boiler sheet.
40 4. In a stay bolt structure, the combination with a boiler sheet and a stay bolt having a head mounted thereon, said head having an annular shoulder, of an annular flexi-

ble cap having one edge bearing against the shoulder on the bolt head and welded to the latter the other edge of said annular flexible cap being welded to the boiler sheet.

5. In a stay bolt structure, the combination with a boiler sheet and a stay bolt having a head mounted in said boiler sheet, said boiler sheet having an annular groove in its outer face surrounding the bearing of the bolt head, of an annular flexible cap having one edge secured in the annular groove in the boiler sheet and having its other edge bearing against the head of the stay bolt.

6. In a stay bolt structure, the combination with a boiler sheet and a stay bolt having a head mounted in said boiler sheet, of an annular flexible cap having two oppositely disposed members, means securing the edge of one member to the boiler sheet, and means securing the edge of the other member to the head of the bolt.

7. In a stay bolt structure, the combination with a boiler sheet and a stay bolt having a head mounted in said boiler sheet, of an annular flexible cap comprising two oppositely disposed members forming a chamber between them, the edge of one of said members secured to the bolt head and the edge of the other member of said cap secured to the boiler sheet, and lubricant within the chamber formed in said cap.

In testimony whereof, I have signed this specification in the presence of two subscribing witnesses.

CHARLES HYLAND.
